M. CHRISTENSEN,
SIGNATURE FOLD CENTERING DEVICE,
APPLICATION FILED DEC. 13, 1919.

Patented Aug. 17, 1920.

UNITED STATES PATENT OFFICE.

MARTIN CHRISTENSEN, OF RACINE, WISCONSIN, ASSIGNOR TO CHRISTENSEN MACHINE CO., OF RACINE, WISCONSIN, A CORPORATION OF WISCONSIN.

SIGNATURE-FOLD-CENTERING DEVICE.

1,349,662.

Specification of Letters Patent. Patented Aug. 17, 1920.

Application filed December 13, 1919. Serial No. 344,698.

To all whom it may concern:

Be it known that I, MARTIN CHRISTENSEN, a citizen of the United States, and resident of Racine, in the county of Racine and State 5 of Wisconsin, have invented new and useful Improvements in Signature-Fold-Centering Devices, of which the following is a description, reference being had to the accompanying drawings, which are a part of this specification.

The present invention relates to certain new and useful improvements in signature fold centering devices for book-stitching machines and has for one of its objects to provide means for centering the folds of signatures or groups of signatures upon the saddle so that the same will be properly positioned to the signature stitcher.

Another object of this invention is to provide means for guiding the signatures as they are fed to the stitching mechanism.

A further object of the present invention is to provide means for guiding signatures along the stitching machine saddle, for centering the folds of the signatures upon the saddle and for frictionally holding the signatures during the stitching operation.

With the above and other objects in view which will appear as the description proceeds my invention resides in the novel construction, combination and arrangement of parts substantially as hereinafter described and more particularly defined by the appended claims, it being understood that such changes in the precise embodiment of the herein described invention may be made as come within the scope of the claims.

In the accompanying drawing I have illustrated one complete example of the physical embodiment of my invention constructed according to the best mode I have so far devised for the practical application of the principles thereof, and in which:

Figure 1 is a front view of a portion of a book-stitching machine and one stitcher mechanism with my invention attached thereto.

Fig. 2 is a plan view of my invention, parts being broken away and in section and 50 the said view being taken on the line 2—2 of Fig. 1, and

Fig. 3 is a view looking at the rear end of the signature engaging portion of my invention.

55 Referring now more particularly to the

accompanying drawing the numeral 5 designates generally a stitcher removably and adjustably carried by the machine frame 6, 7 an inverted V signature-supporting saddle traversing the stitcher 5 and adapted to have groups of signatures 8 fed there along to be stitched by the stitcher 5; and 9 designates generally my novel form of signature fold centering, guiding and holding means.

The signature fold centering member 65 consists of an inverted V saddle or guide 10 adapted to be disposed over the saddle 7 and having a flared leading end 11 for guiding the signatures 8 between it and the saddle, and said member is secured to the lower end 70 of a guide rod or bar 12 freely vertically movably in a pair of aligned arms 13 formed on a supporting member 14 secured to either the stitcher 5 or the frame 6 by suitable fastening means 15.

The rod 12 is capable of free vertical movement and the member 10 is held from engagement with the saddle 7 in the event that a signature 8 is not disposed between the end of said saddle by means of an adjustable stop or set screw 16 carried by the upper end 17 of said rod and engageable with the frame 6 when the member 10 is at its entire lower limit of movement. Thus it will be seen that the signatures 8 which are fed 85 along the saddle 7 by suitable feeding mechanism, not shown, are guided beneath the member 10 by the flaring end 11 and that said member 10 has a slight frictional engagement therewith by reason of its weight 90 and the member 10 being shaped to correspond with the shape of the saddle will center the folds 8' of the signatures with respect to the peak or apex 7' of the saddle and thus properly position the signatures to 95 the stitcher. By reason of the weight of the member 10 engaging the signatures and holding the same between it and the saddle, the signatures 8 will be held substantially firm while being stitched but this frictional 100 engagement is not sufficient to prevent the ready movement of the signatures from the stitcher by the feeding mechanism.

To assist in the positioning of the signatures and to prevent too great a frictional 105 engagement of the member 10 with the signatures I provide a guide roll 18 journally mounted between a pair of up struck space ears or lugs 19 formed at the rear end of the member 10. The roll guide 18 is pro- 110

vided with a **V** channel 20 shaped to correspond with the **V** of the member 10 and the saddle 7. As best shown in Fig. 3 the guide roll 20 engages with the signatures through 5 the aperture formed between the space ears 19 and thus provides means for guiding the signatures and reducing the frictional engagement between the member 10 and said signatures.

10 The top bar 6, against which the adjusting screw 16 engages, is capable of vertical adjustment to adapt the stitchers 5 for different thicknesses of books, thereby simultaneously adjusting my improved fold centering device, as will be obvious. As the adjustable feature of the bar 6 forms no important part of this invention, the manner of operating the same has not been shown.

From the foregoing description taken in 20 connection with the accompanying drawing it will be readily apparent that I provide simple but efficient means for centering folds of signatures upon the saddle for guiding the signatures and for holding the signatures firm and in their proper relation while 25 being stitched.

What I claim as my invention is:

1. In a book-stitching machine, the combination with a stitcher and an inverted substantially **V**-shaped signature supporting saddle traversing the stitcher, of a freely vertically slidably mounted rod mounted above said saddle, and an inverted substantially **V**-shaped signature guide and fold 30 centering member carried by the lower end of said rod and disposed over the saddle to engage the folds of signatures passing along the saddle, said member having its forward end flared to guide the signatures there-

40 beneath.

2. In a book-stitching machine, the combination with a stitcher and an inverted substantially **V**-shaped signature saddle traversing the stitcher, of a rod vertically slidably mounted above the saddle, an inverted substantially **V**-shaped signature guide and

fold centering member carried by the lower end of said rod and disposed over the saddle to engage the folds of signatures passing along the saddle, means on the forward end 50 of said member for guiding signatures therebeneath, and means for at all times retaining the apex of said member in longitudinal alinement with the apex of the saddle.

3. In a book-stitching machine, the combination with a stitcher, an inverted substantially **V**-shaped signature supporting saddle traversing the stitcher, and the stitching machine frame, of a support mounted above 60 said saddle, a rod vertically slidably carried by the support, an inverted substantially **V**-shaped guide and fold centering member carried by the lower end of said rod and disposed over the saddle to engage the folds 65 of signatures passing therealong, a laterally directed portion carried by the upper end of said rod, and means carried by said laterally directed portion for engagement with the machine frame to limit the downward 70 movement of said rod and fold centering member carried thereby.

4. In a book-stitching machine, the combination with a stitcher, and an inverted **V** signature supporting saddle traversing the 75 stitcher, of a support fixed juxtapose the stitcher, a rod vertically slidably carried by the support, an inverted **V** signature guide and fold centering member fixed to the lower end of said rod and disposed over the 80 saddle to engage the folds of signatures passing along the saddle, said member having its forward end flared to guide the signatures therebeneath, an annularly **V** channeled guide roll at the rear end of said 85 member for guiding the signatures, and means at the upper end of said rod for limiting the downward movement of said member.

In testimony whereof, I affix my signature. 90

MARTIN CHRISTENSEN.
